(57) **CLAIM**

The ornamental design for an interior light for vehicles, as shown and described.

DESCRIPTION

FIG. 1 is a perspective view of an interior light for vehicle according to the present invention;

FIG. 2 is a front view thereof;

FIG. 3 is a rear view thereof;

FIG. 4 is a plane view thereof;

FIG. 5 is a bottom view thereof;

FIG. 6 is a left side view thereof; and,

FIG. 7 is an end view taken along A-A' of FIG. 2.

Since the right side view is symmetrical to the left side view, the right side view is omitted.

The ornamental design which is being claimed, as a partial design, is shown in solid lines in the drawings.
